CLAIM

The ornamental design for a display screen or portion thereof with graphical user interface, as shown and described.

DESCRIPTION

FIGS. 1 and 3 are a front view of a display screen or portion thereof with a graphical user interface showing a first embodiment of our new design.

FIGS. 2 and 4 are a front view of a display screen or portion thereof with a graphical user interface in accordance with a second embodiment.

The broken lines, including those showing a display screen or portion thereof and those depicting portions of a graphical user interface, form no part of the claimed design.
